UNITED STATES PATENT OFFICE.

FRANK DZIERZENGA, OF BROOKLYN, NEW YORK.

ELECTRIC WINDOW-CLOSING DEVICE.

Application filed September 29, 1926. Serial No. 136,537.

My invention relates to electric window closing devices and has a particular reference to electromagnetic locking devices adapted to keep window panels in an open position until the magnets of said devices are energized by the electric current, when said locking devices release said panels to be closed by their own weight or by counterweights.

The object of my invention is to provide an electromagnetic device for the above purpose which could be conveniently operated by a push button or by an automatic electric switch actuated by rain. With my mechanism it is possible to have all windows in a house to be controlled by such electromagnetic devices connected with a rain switch, so that as soon as rain starts, all these windows which remained open, will be immediately and automatically closed thereby preventing the rain from getting inside of the house.

I also provide my device with a means whereby the electric circuit is automatically interrupted after the switch has worked once thereby preventing the waste of electric energy.

My invention is more fully described in the accompanying specification and drawing 30 in which—

Fig. 1 is an elevation of my device in an operative position, supporting the window panel in a raised position, Fig. 2 is a diagrammatic view showing arrangement of my 35 devices on a window with two movable panels and with automatic and manual switches, and Fig. 3 is an elevation of my device in an inoperative position.

My device consists of a housing 1 in which 40 a magnet 2 is mounted. An armature 3 is pivotally supported on a lug 4 on said housing with a pin 5. A spring 6 keeps the armature away from the magnet when the latter is not energized and resting against 45 a rest block 7.

A bar 8 is rotatively supported on a bracket 9 with a pin 10. One end of said bar is provided with lugs 11 with a pin 12 on which is pivoted a locking arm 13. A 50 spring 14 tends to keep this locking arm in alignment with the bar 8, the tail end 15 of this arm resting against the central curved portion of the bar 8. A spring 16 tends to turn the bar 8 with the arm 13 into 55 an operating position, as shown in Fig. 1, with the end of the bar 8 locked against the

armature 3, so that the arm 13 can support the weight of a window panel 17 by engaging one of the notches 18 of a metal strip 19 attached to the edge of the panel 17. 60

The bar 8 has a piece of insulation 20 attached to the rear side of its front end and with this insulation it presses against contact springs 21 and 22 bringing them together. These contact springs are interposed 65 in the winding of the magnet 2, so that the circuit through the winding is interrupted when these contact springs are separated.

The frame or housing 1 has lugs 23 for attaching it to the wall or window sash 24. 70

Leads or wires 25 and 26 connect the magnet 2 with a push button or switch 27 through a battery or similar source of electric current 28. Instead of a switch 27 or parallel with it an automatic rain switch 29 75 may be used, operated by a lever 30 with a cup 31 adapted to collect rain drops. The lever is pivoted in the central point, so that the weight of water collected in the cup 31 will cause its turning and closing the circuit. 80

The operation of my device is as follows.

When it is desired to open the window the panel 17 is raised allowing the arm 8 to turn until its rear end catches behind the lower end of the armature 3 in which position it becomes locked. The lug 13 will catch one of the notches 18 and will support the panel 17 in a position desired. The contact springs 21 and 22 will be brought together making possible the closing of the circuit 90 by a switch.

The notched bar 19 may be of any length up to the full height of the panel 17 and it is attached with screws 32.

The panel 17 may be of an ordinary construction and provided with counterweights 33 on ropes 34 suspended on sheaves 35. These counterweights, however, are made light, so that the panel, when left without support, will drop down and close the window. 95

The arm 13 does not interfere with opening of the window or raising of the panel 17, being easily deflected against the spring 14 in a position shown with dotted lines in 105 Fig. 1.

The upper panel 36 is provided with extra heavy counterweights (not shown) so that it slides up and closes the window if left without supporting or retaining device. 110

The locking device for this panel is placed accordingly in an inverted position (shown

with dotted lines in Fig. 2), so that the lug 13 prevents the window panel 36 from moving up.

As soon as the electric circuit is closed, 5 the magnet 2 attracts the armature 3 thereby releasing the arm 8. The weight of the panel will then turn the arm 8 until it takes position shown in Fig. 3, allowing the panel to drop down closing the window. In this 10 position the switch 29 becomes inoperative, the contact springs 21 and 22 being separated, so that the current will not be used if it starts to rain again or the switch 27 and 29 is closed.

15 It is evident that one switch, automatic or manual, can control any number of windows.

Important advantages of my device are 20 that it can retain the window in any position and releases it automatically when the rain starts, also that no current is used after the window has been closed.

I claim as my invention:

1. In a window closing device, the combination with a magnet of an armature in 25 a cooperative relation with said magnet, an arm pivotally supported in a cooperative relation with said armature and adapted to support the window panel in an open position 30, said arm being further adapted to be locked in an operative position with the window panel open by said armature and to be released when said magnet is energized.

35 2. In a window closing device, the combination with a housing, a magnet in said housing, an armature pivotally supported in said housing and adapted to be operated by said magnet, an arm rotatively mounted in 40 said housing and adapted to engage the window panel in an open position and adapted to be locked by said armature, said armature being adapted to release said arm when said magnet is energized, and means 45 to render said magnet inoperative when said window is closed.

3. In a window closing device, the combination with a housing of a magnet in said housing, an armature pivotally supported in 50 said housing, an arm pivotally supported in said housing, a pivotal bar on said arm, said housing being adapted to be attached to the

window frame, the window panel being provided with a plurality of notches, said pivoted bar being adapted to engage one of 55 said notches when said window panel is placed in an open position, said armature being adapted to lock said arm with said pivotal bar in an operative position in an engagement with said window panel, said 60 pivoted bar being adapted to swing out of the way when said window panel is being moved into the open position, and means to retrieve said pivotal bar into its operating position. 65

4. In a window closing device, the combination with a housing adapted to be attached to the window frame, a magnet in said housing, an armature pivotally supported in said housing, a locking arm pivotally supported and adapted to support the window panel in open position, said armature being adapted to lock said locking arm in an operative position, and to release same 70 when said magnet is energized, and contact members on said magnet adapted to be electrically connected together when said locking arm is in an operating position and further adapted to be disconnected when said locking arm is released and placed in 75 an inoperative position thereby disconnecting the circuit through said magnet. 80

5. In a window closing device, the combination with a housing adapted to be attached to the window frame in a coordination with the window panel, a magnet in said housing, an armature in a cooperative relation with said magnet, a locking arm pivotally supported in said housing and adapted to engage said window panel and 90 to retain same in an open position, means to keep said armature in an inoperative position when said magnet is not energized, said armature being adapted to lock said locking arm in an operative position, resilient contact members forming part of a magnet circuit, said locking arm being adapted to connect said contact members together when it is in an operative position, said contact members being adapted to become disconnected when said locking arm is 95 in an inoperative position. 100

FRANK DZIERZENGA.
